US0D1067739S

(12) **United States Design Patent** (10) **Patent No.:** **US D1,067,739 S**
(45) **Date of Patent:** **** Mar. 25, 2025**

(54) **DIGITAL TORQUE WRENCH**

(71) Applicant: **Wuxi Xinlite Precision Technology Co., Ltd.**, Jiangsu (CN)

(72) Inventor: **Xuewei Wang**, Tianjin (CN)

(**) Term: **15 Years**

(21) Appl. No.: **29/912,202**

(22) Filed: **Sep. 14, 2023**

(51) LOC (15) Cl. **08-05**

(52) U.S. Cl.

USPC **D8/24**

(58) **Field of Classification Search**

USPC D8/24, 107, 21, 22, 25; D10/83

CPC B25B 23/1425

See application file for complete search history.

(57) **CLAIM**

The ornamental design for a digital torque wrench, as shown and described.

DESCRIPTION

FIG. 1 is a perspective view of a digital torque wrench design showing my new design.

FIG. 2 is another perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the drawings illustrate portions of the digital torque wrench that form no part of the claim.

1 Claim, 8 Drawing Sheets
